EXTENSIBLE SUPPORTING DEVICE

Eugene Vincent Small, 29760 Hoy Road, Livonia, Mich., and Thomas J. Keim, 14530 Woodmont, Detroit, Mich.

Filed Aug. 13, 1959, Ser. No. 833,609

2 Claims. (Cl. 238—134)

This invention relates to supporting devices for heavy articles such as refrigerators, stoves and the like and, in particular, to extensible supporting devices for such articles.

One object of this invention is to provide an extensible supporting device which enables the moving of a heavy article, such as refrigerator, from its usual position, for repairing or cleaning purposes, yet which will not scar the floor or floor covering, such as linoleum.

Another object is to provide an extensible supporting device of the foregoing character having parallel telescoping extensible track units engaged by rollers mounted on the article, thereby insuring constant alignment of the extension tracks with the main tracks and avoiding the use of swinging extension tracks which scar the floor covering in swinging between their extended and retracted positions.

Another object is to provide an extensible supporting device having tubular telescoping tracks possessing a maximum structural strength capable of supporting heavier articles than it is practical to support by means of angle tracks or channel tracks, the main or outer tubular track also serving as a dust-excluding housing which also conceals the extension track telescoping therewith when retracted therein.

Other objects and advantages of the invention will become apparent during the course of the following description of the accompanying drawings, wherein:

FIGURE 1 is a side elevation of an extensible article-supporting device according to one form of the invention, with the tubular telescoping tracks in their extended positions but with the supported article in its retracted position shown in solid lines and its extended position shown in dotted lines;

FIGURE 2 is a vertical section through the extensible article supporting device of FIGURE 1, taken along the line 2—2 in FIGURE 3, upon an enlarged scale with the tracks in their retracted positions and with the middle portion omitted to conserve space;

FIGURE 3 is a cross-section taken along the zigzag line 3—3 in FIGURE 2; and

FIGURE 4 is a horizontal section taken along the line 4—4 in FIGURE 2.

Referring to the drawing in detail, FIGURE 1 shows an extensible article-supporting device, generally designated 10, for a heavy article 12, such as a refrigerator, stove or the like, adapted to rest upon a floor 14 against a building wall 16. The article 12 is conventional and its details are beyond the scope of the present invention. It is, however, provided with a bottom 18 upon which are mounted two pairs of forward and rearward roller units 20 and 22 respectively, only one pair being shown. Thus, the roller units 20 and 22 are mounted approximately at the four corners of the bottom 18 of the article 12 so as to distribute the weight thereof over the extensible supporting device. The roller units 20 and 22 of each pair form the upper parts of a pair of extensible article-supporting units, generally designated 24 (FIGURE 3), each unit 24 including a telescoping extensible track assembly, generally designated 26.

Each telescoping track assembly 26 in turn includes an outer or main tubular track, generally designated 28, and an inner tubular extension track 30 telescoping therewith, both of the tracks 28 and 30 being preferably of square cross-section for maximum structural strength.

2

The outer tubular track is drilled at intervals and countersunk to receive wood screws or other fasteners 32, reached through access holes 33, by which it is secured to the floor 14 (FIGURES 2 and 3). The outer and inner tubular tracks 28 and 30 are also provided with holes 34 and 36 (FIGURE 3) adapted to be brought into alignment with one another and receive a detent pin 38 secured to the outer or free end of a leaf spring 40, the inner end of which is drilled and secured as by a fastener 42 to the similarly drilled outer tubular track 28 (FIGURE 4). The inner tubular track or extension track 30 is provided with a pair of such holes 36 (FIGURE 2) adapted to register with the detent pin 38 of the detent, generally designated 44, in both the extended and retracted positions of the tubular tracks.

The two outer tubular tracks or main tracks 28 are tied together near their rearward ends by a rearward tie bar 46 of angle cross-section which also serves as a rearward stop for the rearward roller units 22 (FIGURE 2). Similarly, the inner or extensible telescoping tubular tracks 30 are tied together by a forward tie bar 48 of angle cross-section which similarly also serves as a stop for the forward roller units 20. The tie bars 46 and 48 are welded or otherwise secured to their respective tracks 28 and 30 and additionally serve not only to maintain the article-supporting units 24 in spaced parallel relationship but also to enhance the rigidity of the structure formed thereby. The forward tie bar 48 is optionally drilled to receive one or more pull rings or other handles 50 to facilitate extending the extension tracks 30 as shown in FIGURE 1. Secured by welding to the bottoms of the inner or extension tracks 30 is a cross bar 51 which additionally aligns and supports the forward ends of the extension tracks 30.

The forward and rearward roller units 20 and 22 are of similar construction, hence a single description will suffice for both. Each includes an inverted channel-shaped bracket 52, the web 54 of which is secured by suitable fasteners 56 to the bottom 18 of the article 12, and has parallel side walls 58. The latter overlap the outer tracks 28 and are drilled in horizontal alignment to receive a retaining bolt 60 and nut 62. Rotatably mounted upon the axle bolt 60 is the combination outer race and roller 64 (FIGURE 2) which is rollable along the top of the outer or main tubular track 28, and is in turn rollably supported by multiple rollable elements 66, such as bearing balls, upon an inner race 68. These collectively constitute an anti-friction bearing assembly, generally designated 70. The inner race 68 is drilled for the passage of the axle bolt 60, which in turn carries a pair of tubular spacing sleeves 72 (FIGURE 3) interposed between the anti-friction roller assembly 70 and the bracket side walls 56.

In the operation of the invention let it be assumed that the outer or main tubular tracks 28 have been secured by the fasteners 32 to the floor 14 in the location which it is desired that the refrigerator or other article 12 shall normally occupy. Let it also be assumed that the two pairs of forward and rearward roller units 20 and 22 have been secured by the fasteners 56 to the bottom 18 of the article 12 and the latter, with the roller units 20 and 22 thus placed near its four corners, deposited upon the outer tracks 28 with the rearward roller unit brackets 52 resting against the rearward angle tie bar 46 (FIGURE 2). Let it finally be assumed that the inner or extensible tubular track 30 is in its retracted and concealed position within the outer tubular track 28 (FIGURES 2 and 3) with its angle tie bar 48 engaging the brackets 52 of the forward roller units 20, and with the cross bar 51 resting upon the floor 14.

To move the refrigerator or other article 12 into the dotted line position shown in FIGURE 1, the operator

first grasps either the forward tie bar 48 or pull ring or rings 50 thereon, and pulls the tubular tracks 28 from the telescoped or retracted positions of FIGURE 2 to the extended or advanced positions of FIGURE 1. The cross bar 51 moves forward with the tracks 30 and in its forward position distributes the weight at the forward ends of the extension tracks 30 over the floor 14 on which it rests. The operator now pulls or pushes the appliance or other article 12 forward so that its roller assembly 72 of its roller units 20 and 22 roll forward off the main or outer tubular track 28 and onto the extension or inner tubular track 30 into the dotted line position shown in FIGURE 1. The space beneath the normal location of the article 12 may then be cleaned, or repairs made to the back of the article 12 in any suitable manner. When this has been done, the operator pushes the article 12 from its dotted line position of FIGURE 1, rearwardly to its solid line position therein, causing the roller units 22 and 24 to roll backward off the extension tracks 30 and onto the main or outer tracks 28. The operator then pushes the extension tracks 30 back into their telescoped or retracted positions of FIGURE 2 by grasping the forward tie bar 48 or pull handles 50 and pushing rearwardly thereon.

What we claim is:

1. An extensible supporting device for a heavy article, comprising a pair of tubular outer tracks disposed in laterally-spaced parallel relationship and adapted to be

secured to a supporting surface, a pair of tubular inner tracks disposed in telescoping relationship with said outer tracks and in slidable relationship into and out of said outer tracks, two pairs of forward and rearward roller units mounted for longitudinal travel along said outer tracks and secured to said article, said roller units being rollable off said outer tracks onto said inner tracks upon relatively sliding extension of said inner tracks outwardly from said outer tracks, and tie means interconnecting each pair of said tracks.

2. An extensible supporting device, according to claim 1, whereon said tracks are of substantially rectangular cross-section and wherein said roller units are adapted to roll on the tops of said tracks.
